HYDRAULIC WINDING MACHINE

Ferris T. Harrington and James Robinson, Detroit, Mich., assignors to Vickers, Incorporated, Detroit, Mich., a corporation of Michigan

Application January 20, 1940, Serial No. 314,755

5 Claims. (Cl. 242—75)

This invention relates to a hydraulic circuit for furnishing power and control to a winding drum.

The invention has particularly to do with the winding of continuous material such as paper or thread. In such winding operations, which takes place during the manufacture, it is very often essential that a constant tension be maintained on the material as it is being wound. It is also important that the tension be limited in such a way that the continuous material will not break and thus cause an interruption in the manufacturing or other process. Another problem arises due to the fact that as a winding drum is filled with the material, the torque required to rotate the drum increases and some compensation must be made in the speed of the drum to maintain a constant tension.

It is an object of the present invention to provide a hydraulic circuit for winding material at a constant tension and at a constant horsepower input with the speed of the winding drum varying indirectly as its resisting torque.

A further object of the invention has to do with a hydraulic means for limiting the acceleration of the winding drum as it is started into movement in order that there will be no breakage resulting from a sudden start.

Other objects and features of the invention, having to do with details of construction and operation of the various elements of the circuit, will be further brought out in the following description and claims.

In the drawing:

Fig. 1 consists of a circuit with certain elements of the circuit shown diagrammatically and other elements shown in cross section.

Fig. 2 is a side view of a winding drum.

Fig. 3 is a schematic section of the flow control valves.

Referring to Fig. 1, the elements of the circuit which are directly concerned with power transmission to a winding drum 5 are: an electric motor 6, a variable delivery pump 7 driven by the motor 6 and having a volume control cylinder block 8, a variable torque hydraulic motor 9 connected to the drum 5 and having a movable torque control member 10, and a torque control motor indicated generally at 11. The general type of pump 7 and motor 9 is shown in Patent No. 2,177,097 of October 24, 1939, to Doe et al., and Patent No. 2,200,811 of May 14, 1940, to Thompson.

The circuit which has specifically to do with the starting and control of the acceleration of

the winding drum consists generally of a constant delivery pump 12 driven by motor 6, a four-way valve 13, a speed control device 14 and a flow control feed valve 15.

5 The variable delivery pump 7 is of a well-known variable piston displacement type in which the cylinder block 8 is movable from a stop-minimum volume position shown by the dotted lines in Fig. 1 to a maximum volume position shown by the full lines in Fig. 1. The speed control device 14 consists of a cylinder 16 having a piston 17 slidable therein. A piston rod 18 and a link 19 connect the piston 17 with the cylinder block 8. A screw 20 is provided at the bottom of the cylinder 16 to limit the maximum volume position of the cylinder block 8. The outlet of the pump 7 is connected to the inlet of the motor 9 by a conduit 21 in which is located a maximum relief valve 22 and the outlet of the motor 9 is connected to a tank 23 by a conduit 24 which also connects with the relief valve 22. The variable torque motor 9 is of the well-known variable piston displacement type. The movable torque control member 10 may be shifted from a stop-minimum torque position shown in the dotted lines in Fig. 1, to any of a number of speed positions, one of them being illustrated by the full lines of Fig. 1.

20 The torque control motor 11 consists of a cylinder 25 which has a piston 26 slidable therein. A piston rod 27 projects from both ends of the piston 26 through both ends of the cylinder 25 and a link 28 connects one end of the piston rod with the movable block 10. The top end of the cylinder 25 is connected by a conduit 29 to the inlet conduit 21 of the motor. The lower end of the cylinder 25 is connected to the tank conduit 24 by a conduit 30 which leads through an adjustable check valve 31. This check valve has a screw 32 for adjusting a spring 33. The conduits 29 and 30 are connected through a restriction 34 which enters the conduit 30 between the check valve 31 and the cylinder 25. A spring 35 is positioned in the lower end of the cylinder 25 to urge the piston 26 upwardly. The function of this spring will be brought out later.

25 Referring now to the starting and acceleration control circuit, the outlet of the constant delivery pump 12 is connected to the four-way valve 13 through a conduit 38 which passes through a relief valve 39. The four-way valve 13 has two tank connections 40 and 41 which lead to the tank conduit 24. Between the four-way valve and the top of the cylinder 16 is a conduit 42. The lower end of the cylinder 16 is connected to the

four-way valve 13 through a conduit 43 which branches at its mid-section into two conduits 44 and 45. A check valve 46 is provided in the conduit 44 which will permit pressure liquid to pass from the valve 13 to the lower end of the cylinder 16. In the conduit 45 is the flow control valve 15. This valve 15 is adapted to provide for a constant flow of liquid from the lower end of the cylinder 16 to a tank connection of the four-way valve 13. The flow control valve is shown in Fig. 3 as having a housing 15 which is provided with a chamber 153 in communication with the incoming liquid and a chamber 154 for connecting a balanced inlet valve 155 and a variable orifice outlet valve 156. This outlet valve 156 controls the volume of liquid passing into the outlet 157.

The balanced valve 155 is connected by means of a stem 158 to a piston 159, the diameter of the stem at point 160 being predetermined relative to the effective diameter of the valve 155 at its valve seat. A coil spring 161 of predetermined pressure is so positioned as to tend to open valve 155. The chamber 154 is in direct communication with a chamber 162 on one side of the piston 159 by means of a passageway 163 so that the strength of the spring 161 as balanced against the pressure upon the area of the piston 159 determines the opening of valve 155. A passage 165 compensates for any back pressure. There is therefore a constant differential pressure across the orifice 156 regardless of back pressure.

A complete description of the operation of the valve 15 may be found in Vickers Patent No. 2,272,684, issued February 10, 1942. The four-way valve 13 has a valve spool 47 slidable therein connected by suitable links to an operating lever 48. This lever is movable from a full line start position as shown, to stop position, indicated by dotted lines.

The continuous material being wound on the winding drum 5 is indicated at 50 in Figs. 1 and 2. This material passes over a guide 51 and the dotted line 52 shows the diameter of the drum after a quantity of the material has been wound thereon.

In the operation: Assuming that the electric motor 6 is operating, pressure will be available from pumps 7 and 12. When the circuit is at rest, the block 8 of pump 7 will be in the dotted line position shown in Fig. 1. The lever 48 may then be moved to start position as shown. In this position, low pressure liquid from pump 12 will pass from the conduit 38 through four-way valve 13 to conduit 42 and the piston 17 will be moved downwardly. However, the rate at which this piston may move downwardly is positively controlled by the rate at which liquid in the lower portion of the cylinder 16 may pass through the flow control valve 15. This liquid will pass from the conduit 43 through the flow control valve at a definite rate depending on the adjustment of the valve and then through the four-way valve to the tank connection 40. As the piston 17 moves downwardly the cylinder block 8 will be moved, so that liquid under pressure, will gradually be directed in increasing volume to the motor 9. This will start the winding drum 5 since the shaft of the motor 9 is suitably connected to the winding drum. As the motor 9 accelerates, the piston 17 will gradually reach its lowermost position, as shown in the full lines in Fig. 1. This position will be maintained by pressure from the pump 12 and the discharge of pump 12 will then be bypassed

to the tank from the pressure relief valve 39. By adjusting the stop screw 20, the average speed desired for the motor 9 may be predetermined.

Due to the small drum diameter at the beginning of a winding operation, the torque required to rotate the drum will be relatively low and the R. P. M. of the drum will be high. As the drum is filled with material, the torque required increases and the R. P. M. of the drum should decrease in order to maintain a constant tension on the material. As soon as the variable delivery pump 7 begins to direct fluid under pressure to the motor 9, fluid will also be supplied to the top of the piston 26 through conduit 29. The lower end of the cylinder 25 will receive fluid from conduit 29 through the restriction 34. Since the upper and lower working areas of the piston 26 are equal, the piston will be pressure balanced. The spring 35 is of sufficient strength to cause the piston 26 to offset the torque control member 10 to the high speed minimum torque position as shown by the dotted lines in Fig. 1. As the diameter of the paper on the drum increases, the torque requirements to keep the drum turning also increase. This places an increasing load on motor 9 and increases the pressure in conduit 21. When the pressure of the liquid in the conduit 21 and below the piston 26 exceeds the setting of relief valve 31, fluid will be exhausted from below the piston at a faster rate than it can be supplied through the restriction 34. As a result the piston is no longer balanced and the pressure in the upper chamber is sufficient to overcome the spring 35 and actuate the piston 26 to increase the displacement of the member 10. This will reduce the R. P. M. of the motor 9 and increase the torque of the motor until the torque is sufficient to rotate the drum 5 with the pressure at the setting of the relief valve 31. During the operation, the relief valve 22 protects the main circuit from excessive pressures.

If, in the course of the winding, any additional resistance occurs to the movement of the continuous material 50, the increase in torque exerted on the drum 5 will be transmitted to the motor 9 and speed will be proportionately reduced so that at all times a constant tension is exerted on the material being wound. When the winding drum has been filled to the proper diameter, the motor 9 may be stopped by shifting the control lever 48 to its stop position shown in dotted lines in Fig. 1. This will shift the piston 47 upward in the four-way valve 13 and connect the lower end of the cylinder 16 to the pressure line 38. The fluid under pressure will pass to the cylinder through conduits 43 and 44 and the check valve 46. There will be a resulting movement upward of the piston 17, the liquid above the piston being directed to the tank through conduits 42 and tank connection 41. This movement upward of the piston 17 will shift the cylinder block 8 to its stop-minimum volume position, as shown in the dotted lines of Fig. 1. Consequently, liquid under pressure will no longer be directed to the inlet of the motor 9. It will be seen that if it were desired to bring about a gradual stopping of the drum 5 as well as the gradual starting, a flow control valve 15 would be inserted in the conduit 42 in the same manner as shown with conduit 43.

We claim:

1. In a constant tension winding machine adapted for winding continuous material, of the type having a variable delivery pump as a source of pressure, a winding drum, and a fluid actuated motor connected to said winding drum and arranged to receive fluid under pressure from said variable delivery pump, a control device for said pump comprising a movable means on said pump shiftable from a minimum volume position to a maximum volume position for varying the volume of fluid delivered to said motor, an auxiliary pump, power means for driving said pumps, hydraulically actuated means connected to said movable means, means for directing fluid from said auxiliary pump to said hydraulically actuated means whereby said movable means may be shifted to any of its various positions, and means effective on said hydraulically actuated means for limiting the rate of movement of said movable means from the minimum volume position to any higher volume position whereby said winding drum will be accelerated gradually to avoid breakage of the material being wound.

2. In a device for reeling strip material of the type including a reel, driving means for the reel including a variable delivery fluid pump and a fluid motor driven by the pump, fluid conduits forming supply and return conduits between the pump and motor, and control means for maintaining a constant peripheral tension on the material being reeled including means responsive to the fluid pressure developed by the motor in the supply connection for varying the displacement of the motor, a means for limiting the initial tension in the material being reeled comprising a pressure responsive auxiliary motor for varying the displacement of the pump, a source of pressure for operating said auxiliary motor, and means limiting the exhaust flow from said auxiliary motor for controlling the rate at which displacement of said pump may be changed.

3. In a device for reeling strip material of the type including a reel, a driving means for the reel including a variable delivery fluid pump and a fluid motor driven by the pump, fluid conduits forming supply and return conduits between the pump and motor, and control means for maintaining a constant peripheral tension on the material being reeled including means responsive to the fluid pressure developed by the motor in the supply connection for varying the displacement of the motor, said conduits being arranged to deliver to the motor the full discharge of the pump during normal operation, a means for limiting the initial tension in the material being reeled comprising a control device for the output of said pump including a movable means on said pump shiftable from a minimum to a maximum volume position, an auxiliary source of pressure, a piston-cylinder control motor for controlling the position of said movable means, means connecting said auxiliary source of pressure with one side of said control

motor, and means connecting the other side of said control motor with a flow control device for limiting the flow of liquid and the rate of movement of said control motor.

5. In a device for reeling strip material of the type including a reel, driving means for the reel including a variable delivery fluid pump and a fluid motor driven by the pump, fluid conduits forming supply and return conduits between the pump and motor, and control means for maintaining a constant peripheral tension on the material being reeled including means responsive to the fluid pressure developed by the motor in the supply connection for varying the displacement of the motor, said conduits being arranged to deliver to the motor the full discharge of the pump during normal operation, a means for limiting the initial tension in the material being reeled comprising a control device for the output of said pump including a movable means on said pump shiftable from a minimum to a maximum volume position for varying the volume of fluid delivered to said motor, an auxiliary pump, power means for driving said pumps, hydraulically actuated means connected to said movable means, means for directing fluid from said auxiliary pump to said hydraulically actuated means whereby said movable means may be shifted to any of its various positions, and means effective on said hydraulically actuated means for limiting the rate of movement of said movable means from the minimum volume position to any higher volume position whereby said winding reel will be accelerated gradually to avoid breakage of the material being wound.

35. 5. In a device for reeling strip material of the type including a reel, driving means for the reel including a variable delivery fluid pump and a fluid motor driven by the pump, fluid conduits forming supply and return conduits between the pump and motor, and control means for maintaining a constant peripheral tension on the material being reeled including means responsive to the fluid pressure developed by the motor in the supply connection for varying the displacement of the motor, said conduits being arranged to deliver to the motor the full discharge of the pump during normal operation, a means for limiting the initial tension in the material being reeled comprising a volume controlling member on said delivery pump, means for limiting the acceleration of said motor to avoid breakage of said material being wound comprising an auxiliary source of pressure, hydraulically actuated means operably connected with said volume control member, means for directing said auxiliary pressure to said hydraulically actuated means to shift the same to increase or decrease the volume output of said variable delivery pump, and means for limiting the rate of movement of said volume control member from a minimum position to any higher volume position to limit the acceleration of the variable delivery motor.
